United States Patent

Des. 236,224

Patented Aug. 5, 1975

236,224

EARRING

Helen J. Hardison, 8218 Ponnel, Houston, Tex. 77088

Filed Aug. 7, 1973, Ser. No. 386,458

Term of patent 14 years

Int. Cl. D11—01

U.S. Cl. D45—9

The figure is a perspective view of an earring showing my new design.

The braiding pattern on the opposite side is identical to that shown.

I claim:

The ornamental design for an earring, substantially as shown and described.
